(57) **CLAIM**

The ornamental design for a data transmission device, as shown and described.

DESCRIPTION

FIG. 1.1 is a front-perspective view of a data transmission device.
Figure 1.2 is a right-side view of the data transmission device.
Figure 1.3 is a front-side view of the data transmission device.
Figure 1.4 is a rear-side view of the data transmission device.
Figure 1.5 is a left-side view of the data transmission device.
Figure 1.6 is a top view of the data transmission device.
Figure 1.7 is a bottom view of the data transmission device.
